CHICK FEEDER

Louis A. Shoemaker, Carleton, Mich.

Application September 5, 1939, Serial No. 293,311

18 Claims. (Cl. 119—61)

This invention relates to feeders for baby chicks, or the like, and more particularly to those made of sheet material, such as paper board or the like, and which can be shipped and sold flat and then set up in form for use by the poultry raiser.

Generally stated, the object of the invention is to provide a novel and improved construction whereby a feeder of this kind is provided that has the advantages of relative cheapness, better strength and durability in use, as well as certain features of improvement tending to prevent interference in feeding at the opposite sides thereof, as will hereinafter more fully appear.

15 To the foregoing and other useful ends, the invention consists in matters hereinafter set forth and claimed, and shown in the accompanying drawings, in which—

Fig. 1 is a perspective of a feeder embodying 20 the principles of the invention.

Fig. 2 is a top plan view of the feeder.

Fig. 3 is an enlarged cross section on line 3—3 in Fig. 1 of the drawings.

Fig. 4 is an enlarged fragmentary section on 25 line 4—4 in Fig. 2 of the drawings.

Fig. 5 is a plan view of the single blank from which the said feeder is made.

Fig. 6 is a fragmentary perspective view showing a different form of the invention.

30 Fig. 7 is a plan view of what is shown in Fig. 6.

Fig. 8 is a plan view of one end portion of the blank from which the chick feeder shown in Figs. 6 and 7 is made.

As thus illustrated, the invention comprises an 35 oblong rectangular trough like body having side walls 1 and end walls 2, with a bottom 3 and top wall sections 4, the latter having feeding openings 5 therein. Between the said openings there is an integral vertical panel formed of two sections 6 disposed flatwise together. These panel

40 sections have end tabs 7 that project through the slots 8 in the end walls 2, the latter tapering upward to the upper edge of said panel, and the slots 8 being preferably enlarged at the middle to 45 facilitate the insertion of said tabs. The latter are bent apart, as shown, to keep them from pulling out, and this is facilitated by the notch 9 in one of each of the two pairs of tabs.

It will be seen that the top wall sections have 50 end tabs 10 to interlock with the end walls, just above the shoulders 11 of said end walls.

Thus the boxlike structure is strong and durable and put together without any glue or staples or other fastening means.

55 Preferably the entire feeder is made from a

single blank cut and formed as shown in Fig. 5 of the drawings.

The said panel separates the chicks at one side from those at the other, and prevents pecking across the feeder, it being observed that the portions 12 displaced from the feed openings 5 form a base extension of the panel into the feeder, thus in-effect dividing the latter into two parallel separate feed troughs.

The upper edge of the said panel is relatively 10 thin and serves to discourage roosting thereon, which would be objectionable.

As shown, the ends 13 of the side walls extend a distance beyond the end walls 2, thus providing 15 strong corner construction.

As shown in Figs. 6, 7, and 8, the construction is practically the same as that previously shown and described, except that the tabs 10 are omitted, and the shoulders 11 are not employed.

Thus a single blank of paper board or similar 20 material forms the entire feeder with its said advantageous panel, upon which latter advertising matter may be printed if desired.

It will be seen that with the practically or 25 approximately horizontal top formed by the top wall sections 4 of the blank, the feeder can be filled with food, entirely full, as it will not spill out through the openings in the top wall. Also,

if any of the chick feed falls on the top wall, it will not slide off onto the ground, as this wall 30 is almost, if not quite, horizontal. The single blank from which the feeder is made comprises a bottom section and side wall and top wall sections, together with panel sections, and it will be seen that parallel fold lines are provided between 35 all of these sections. In the feeder, after the blank is properly folded, it will be seen that the inner edge of each opening 5 is formed by the base portion of the vertical panel, which latter extends vertically a substantial distance above 40 the horizontal plane of the said feeding openings. The blank is easily folded without danger of tearing or breaking any portion thereof. In addition, it will be seen that the vertical panel formed by the blank sections 6 serves as a longitudinal tie 45 rod to prevent outward displacement of the end walls 2 of the boxlike feeder. This means that it functions to resist longitudinal or endwise bursting strain tending to blow out the ends of the box. Thus, the top walls 4 are entirely or at 50 least almost relieved of any necessity of holding the end walls 2 against outward displacement, the entire blank being held in folded condition by the said longitudinal panel, as illustrated in Figs. 6, 7 and 8, and practically so in Figs. 1 and 2 55

of the drawings. This is because the tabs 1, when bent as shown in Figs. 2 and 7, resist outward displacement of the said end walls of the boxlike structure. Moreover, it is important to observe that the end walls 2 serve to hold the panel or divider 6 against upward displacement. This is because the end walls have portions that extend over and engage the upper edges of the tabs or interlocking portions 1 that extend through the slots 8 of the end walls. Thus the said panel serves to restrain the end walls against outward displacement, and the end walls hold the panel against upward displacement.

It is also important to observe that the portions 12 that are cut out of the blank, to form the feeding openings 5 are not thrown away, as they remain in the feeder to form the base of the vertical panel.

It is important to observe that, in each form 20 of the invention, the fold line between the end wall 2 and the bottom 3 is in alignment with straight end edges of the sections 4 and 6 of the blank. This tends not only to simplify the forming and cutting of the blank, but also the folding 25 thereof.

What I claim as my invention is:

1. A feeder for baby chicks or the like, all formed from a single foldable blank, comprising a rectangular one-piece boxlike structure of substantially greater length than width, having side and top and bottom and end walls, the bottom wall extending integrally and continuously from one side wall to the other, and having a longitudinally disposed vertical panel connecting the two end walls together to serve as a tie rod between the two end walls, preventing outward displacement of the latter, and serving also as a divider of substantial height between the two opposite sides of the feeder, but with the lower edge of said divider spaced a distance above said bottom wall, and the fold lines of the end walls being in the same plane as portions of the end edges of the top wall and with portions of the end edges of the panel.

45 2. A structure as specified in claim 1, said top wall comprising two sections formed integrally with the lower edge of said panel and with longitudinally disposed parallel feed openings therein, said panel forming the straight inner side of each opening.

3. A structure as specified in claim 1, comprising two sections disposed flatwise together to form said panel, so that the latter has two separate edges pressed close together, the end walls 55 having vertical slots therein, and the panel sections both having end tabs that engage and interlock with said slots.

4. A structure as specified in claim 1, said top wall comprising two sections at opposite sides of 60 said panel, disposed above the lower edge of the latter, these sections being almost, if not quite, horizontal when the feeder is viewed in transverse cross section.

5. A structure as specified in claim 1, said end 65 walls having portions that extend transversely across upper edges of end portions of said panel, thus holding the latter down, but with the main portion of said panel extending above these upper edges.

70 6. A structure as specified in claim 1, said panel having vertical portions depending within the feeder, which depending portions fit openings in the top wall when the blank is spread out flat.

7. A structure as specified in claim 1, said top 75 wall having corner portions that hook around the

side edges of the end walls, with these hook portions spaced apart on the outer side of each end wall.

8. A structure as specified in claim 1, said top wall having corner portions that hook around the 5 side edges of the end walls, with these hook portions spaced apart on the outer side of each end wall, the latter having shoulders engaging the under side of the top wall.

9. A structure as specified in claim 1, said panel 10 comprising two straight sections held flatwise together and held against upward displacement by said end walls, the latter having slots each holding the two sections of the panel pressed together.

15 10. In a feeder for baby chicks and the like, all formed from a single foldable blank, having a top wall with feed openings therein, a longitudinal vertical panel extending a distance above said openings, between the openings at one side and 20 those at the other, with the lower edge of the panel spaced a distance above the bottom of the feeder, and end walls including engaging means on the opposite ends of the feeder to positively hold the panel against upward displacement, but 25 having separable engagement therewith, and the fold lines of the end walls being in the same planes as portions of the end edges of the top wall and with portions of the end edges of the panel, said engaging means extending a substantial distance beyond all other parts when the blank is spread out flat, thus providing end walls 30 that extend to the upper edge of the panel:

11. A structure as specified in claim 10, having the bottom wall extending continuously from end 35 to end and from side to side of the feeder, and with the lower edge of the panel extending downward a distance into the interior of the feeder.

12. A structure as specified in claim 10, the 40 apertured top wall being integral at the transverse middle of the feeder with the base of said panel, the latter having two separate top edges pressed together by engagement of the ends of the panel with the ends of the feeder.

13. A structure as specified in claim 10, the 45 apertured top wall being integral at the transverse middle of the feeder with the base of said panel, with base portions of the panel fitting said openings when the blank is spread out flat.

14. A feeder for baby chicks or the like, all 50 formed from a single foldable blank, comprising a rectangular boxlike structure of substantially greater length than width, having side and top and bottom and end walls, and having a longitudinally disposed vertical panel connecting the 55 two end walls together to serve as a tie rod between the two end walls, preventing outward displacement of the latter, and serving also as a divider of substantial height between the two opposite sides of the feeder, said panel having vertical portions depending within the feeder, which depending portions fit openings in the top wall when the blank is spread out flat.

15. A feeder for baby chicks or the like, all 65 formed from a single foldable blank, comprising a rectangular boxlike structure of substantially greater length than width, having side and top and bottom and end walls, and having a longitudinally disposed vertical panel connecting the 70 two end walls together to serve as a tie rod between the two end walls, preventing outward displacement of the latter, and serving also as a divider of substantial height between the two opposite sides of the feeder, said top wall having corner portions that hook around the side edges 75

of the end walls, with these hook portions spaced apart on the outer side of each end wall, the latter having shoulders engaging the under side of the top wall.

5 16. In a feeder for baby chicks and the like, having feed openings in the top wall thereof, a longitudinal vertical panel extending a distance above said openings, between the openings at one side and those at the other, and means on the 10 ends of the feeder to positively hold the panel against upward displacement, but having separable engagement therewith, said top wall being integral at the transverse middle of the

feeder with the base of said panel, all formed of a single blank, with base portions of the panel fitting said openings when the blank is spread out flat.

17. A structure as specified in claim 16, said 5 base portions forming a double lower edge for the panel, and the latter also having a double top edge.

18. A structure as specified in claim 16, said base portions being flatwise together in the working condition of the feeder.
